UNITED STATES PATENT OFFICE.

AUGUST OBERNOLTE, OF HENDERSON, MINNESOTA, ASSIGNOR TO UNDERWOOD TYPE-WRITER COMPANY, OF NEW YORK, N. Y., A CORPORATION OF NEW JERSEY.

TYPE-WRITING MACHINE.

Specification of Letters Patent.

Patented Feb. 1, 1910.

948,146.

Application filed November 29, 1909. Serial No. 530,326.

To all whom it may concern:

Be it known that I, AUGUST OBERNOLTE, a citizen of the United States, residing in Henderson, in the county of Sibley and State of Minnesota, have invented certain new and useful Improvements in Type-Writing Machines, of which the following is a specification.

This invention relates to stop devices for arresting typewriter carriages, and particularly to devices coöperating with the right hand adjustable marginal gage on the framework of the machine.

The invention is an improvement on the mechanism shown in patent to Helmond No. 853,242, issued May 14, 1907, in which a substantial increase in the width of the left hand margin on the sheet was attained by providing, in addition to the usual lever-actuated stop, an auxiliary stop usable independently of the main stop and coöperating with the usual margin gage. The auxiliary stop was mounted on a second lever pivoted to the main stop lever, and detained by a cam on said second lever, both stops being releasable by the usual release key on the main lever.

The object of the present invention is to provide a simple, inexpensive device of this nature, whereby the regulation of the width of the left hand margin of the sheet is effected in a more rapid and facile manner than heretofore.

According to my invention, I mount an auxiliary stop directly on the usual spring-actuated margin-regulating lever in advance of the main stop thereon, and provide simple means for mechanically detaining the main lever itself in one position, against the tension of its spring, to hold said auxiliary stop in effective position relative to the margin gage.

In the accompanying drawings, Figure 1 is a perspective view of one embodiment of my invention applied to the Underwood type of front strike machine, parts being broken away to better disclose the construction. Fig. 2 is a detail view in side elevation showing the normal positions of the carriage stops. Fig. 3 is a detail top plan view of the detent in idle position shown in Fig. 2. Fig. 4 is a detail view in side elevation, showing the stop-carrying lever swung to its opposite position. Fig. 5 is a detail end view showing the position assumed by the detent

when holding the stop-carrying lever in its Fig. 3 position. Fig. 6 is a top plan view of the parts in the position shown in Fig. 4.

A carriage 1, mounted to travel on the framework 2 of a typewriting machine, has a margin regulating lever 3 pivoted intermediate its ends, as at 4, one arm of the lever having a main stop 5 for contact with a margin gage 6. The latter is adjustable along a rod 7 on the framework 2, and provided with teeth 8 to engage a rack 9 on a stationary rail 10, and thereby hold the gage 6. A spring 11 yieldingly holds the lever 3 in one of its positions, to maintain the stop 5 depressed to a point where it may engage the gage 6. Whenever it is desired to write on the margin, the lever 3 is rocked by a key 13 on the outer arm of the lever, opposite from the main stop 5, to release said stop 5 and permit the carriage to run beyond the gage 6. Owing to the shortness of the rack 9 and to the presence of a fixed collar 12 on the guide rod 7, the range of adjustment of the main margin gage 6 is only about one half the range of travel of the carriage, thereby restricting the regulation of the width of the left hand margin on the sheet. To obtain an increase in the width of the left hand margin, I mount an alternately usable auxiliary stop 18 directly upon the outer arm of the margin-regulating lever, a considerable distance to the right of the main stop 5. This auxiliary stop 18 normally is out of use, but is thrown into effective position when the key 13 is depressed.

When the operator desires to leave a narrow margin on the sheet, he will leave the lever 3 in its normal spring-maintained position, shown in Fig. 2, so that the main stop 5 lies in effective position relative to the margin gage 6 to arrest the carriage on its return travel from the end of the previous line, variations in the width of margin throughout the latter portion of the return travel of the carriage being attained by adjusting the margin gage 6 on the rack 9. When the main stop 5 is in use, the auxiliary stop 18 lies out of use and vice versa. Should the operator wish to leave a very wide margin, or to write a column on the right hand side of the sheet, he will depress the key 13 to rock the lever 3 against the tension of a spring 11, to the position shown in Figs. 1, 4 and 5. The depression of the key 13 and the outer arm of the lever, at once

silences the main stop 5 and brings the auxiliary stop 18 into use. Since said auxiliary stop 18 is located a considerable distance to the right of the main stop 5, it can coöperate with the gage 6 while the carriage is at the left-hand portion of its travel, thereby materially increasing the possible width of the left hand margin on the sheet. For example, the distance between the stops 5 and 18 may be nearly equal to one-half of the range of travel of the carriage, and hence the auxiliary stop 18, together with the gage 6, would effect the arrest of the carriage at any point in the first half of the return travel thereof, whereas, the main stop 5 would be capable of arresting the carriage only at any point in the latter half of such return travel. The rocking of the lever 3 to bring the auxiliary stop 18 into effective position relative to the margin gage 6, throws the main stop 5 to ineffective position, as shown in Figs. 1 and 4. Thus the depression of the key 13 and the spring 11 operates to throw the lever to one or the other of its positions to alternately bring one stop or the other into use.

To mechanically hold the main lever 3 against the tension of its spring 11 so that the normally idle auxiliary stop 18 is in use, I conveniently arrange the circular key disk or button 13 itself to act as a detent by pivoting it upon the outer arm of the margin-regulating lever 3, as at 14. After the key disk 13 has been depressed to rock the lever 3 and bring the auxiliary stop 18 into use, said key disk is rotated to cause its edge to enter a slot 16 formed in a part 17 of the carriage, to detain the lever 3 and auxiliary stop 18 in depressed position. To permit the key disk 13 to clear the part 17, so that the lever may be depressed and elevated, I cut away one edge of the circular key disk, as at 15. When the cut away edge of the disk lies adjacent to the part 17, the key 45 may be freely depressed and elevated. A slight rotation of the disk, when in depressed position, engages it in or disengages it from the slot 16.

Preferably the stop 18 is rigid on the lever 3, and it is obvious that the operation of the single margin-regulating lever controls both main and auxiliary stops, which are alternately thrown into and out of effective position relative to the margin gage. Having thus described my invention, I claim:

1. In a typewriting machine having a framework and a carriage, the combination with a margin gage on the framework, of a lever on the carriage, main and auxiliary stops on the lever, the auxiliary stop normally held in idle position by the lever which is shiftable to reverse the operative relationship of the main and auxiliary stops relative to the gage to effect a variation in the width of the margin on the sheet. 60

2. In a typewriting machine having a framework and a carriage, the combination with a margin gage on the framework, of a lever on the carriage, main and auxiliary stops on the lever, the auxiliary stop normally held in idle position by the lever which is shiftable to reverse the operative relationship of the main and auxiliary stops relative to the gage to effect a variation in 70 the width of the margin on the sheet, and locking means for holding the lever in shifted position when the auxiliary stop is brought into use. 75

3. In a typewriting machine having a carriage and a framework, the latter having a margin gage, of a lever pivoted on the carriage, main and auxiliary stops carried by the lever on opposite sides of its pivotal support, respectively to enable the lever to 85 throw the stops alternately into and out of operative position relative to the gage. 80

4. In a typewriting machine having a carriage and a framework, the latter having a margin gage, of a lever having main and auxiliary stops coöperating with the margin gage, a key disk rotatably mounted on the lever and having a portion of its edge cut away, the unmitigated edge receivable in a notch in the carriage to mechanically detain 95 the auxiliary stop in operative position relative to the gage. 90

5. In a typewriting machine, the combination with a carriage and a framework, the latter having a margin gage, of a shiftable lever carrying a stop having an effective and an ineffective position relative to the gage according to the position of the lever, a spring normally maintaining the lever in one of its positions, and a detent for mechanically detaining the lever in another of its positions against the tension of the spring. 100 105

AUGUST OBERNOLTE.
